UNITED STATES PATENT OFFICE.

GEORGE KÜHN, OF ST. LOUIS, MISSOURI.

DESIGN FOR A HOUSING OR FRAME FOR SASH-PULLEYS.

SPECIFICATION forming part of Design No. 17,173, dated March 8, 1867.

Application filed February 1, 1867. Serial No. 226,197. Term of patent 14 years.

To all whom it may concern:

Be it known that I, GEORGE KÜHN, a citizen of the United States, residing at St. Louis, in the State of Missouri, have invented and 5 produced a new and original Design for Sash-Pulleys, of which the following is a specification.

The nature of my design is illustrated in the accompanying drawing, being a perspective 10 view of the sash-pulley, which consists of the face-plate H H, the curved parts A A, partition B, perforations C C D D, and swelling or 15 projections E upon the outside of each of the flanges F F, and extending from near the base of the perforations C C to and almost enveloping the part G, thence to the inside of the face-plate H. The perforations C C are parallel with each other midway between the curved

parts A A and the top of the flanges F F and upon either side of the partition B. They are 20 already secured to me by design patent issued November 9, 1866, Serial No. 215,109.

I claim—

The design for the housing or frame for sash-pulleys, the same consisting of the face-plate 25 H, having the curved parts A A, partition B, and swelling or projections E, as shown and described.

In testimony whereof I have signed my name to this specification in the presence of two 30 sub-scribing witnesses.

GEORGE KÜHN.
